UNITED STATES PATENT OFFICE.

PATRICK F. MARA, OF DANVERS, ILLINOIS.

CUT-OUT FOR AUTOMOBILES.

1,217,800.

Specification of Letters Patent. Patented Feb. 27, 1917.

Application filed May 22, 1915. Serial No. 29,876.

To all whom it may concern:

Be it known that I, PATRICK F. MARA, a citizen of the United States, residing at Danvers, in the county of McLean and State of Illinois, have invented new and useful Improvements in Cut-Outs for Automobiles, of which the following is a specification.

This invention relates to cut-outs for automobiles, motor cars and the like, the object in view being to do away with the present chain and pulley connections for operating the cut-out in the exhaust pipe of the engine and the troubles incident to the use thereof such as the wearing out of the chain and the binding of the chain on the pulleys, and to utilize in place thereof lever and spring connections which afford a practical control for the cut-out and which are not subject to wear, displacement and dislocation as in the case of the present day cut-out operating mechanism.

With the above and other objects in view, the invention consists in the novel construction, combination and arrangement of parts, as herein described, illustrated and claimed.

In the accompanying drawings:—

Figure 1 is a bottom plan view of a sufficient part of a motorcar to illustrate the application of the present invention thereto. Fig. 2 is a side elevation partly in longitudinal section of the same.

Referring to the drawings A generally designates the body of a motorcar and 2 a portion of the chassis thereof, 3 designating the driver's seat, 4 the front platform or floor in front of the driver's seat, 5 the engine of the car and 6 the exhaust pipe which in the well known Ford machine extends rearwardly from the engine to a point adjacent to the rear end of the car where it is provided with a muffler 7.

In carrying out the present invention, I employ a cut-out designated generally at B comprising a section of the exhaust pipe 8 which is located in close proximity to the engine in order that the exhaust may be liberated into the atmosphere as soon as possible after leaving the combustion chamber or chambers of the engine. 8' designates a disk-shaped valve which forms the cut-out proper, said valve being mounted in a T-shaped tubular extension 9 of the section of the exhaust pipe in which the cut-out is mounted. The disk-shaped valve or cut-out proper comprises a shaft or a stem 10

which is journaled at diametrically opposite points in the extension 9 of the exhaust pipe, said shaft or stem extending laterally and projecting beyond one side of said section where it has mounted fast thereon an operating arm 11.

The operating arm 11 is provided adjacent to its extremity with a hole 12 in which is received one extremity of a coiled contractile spring 13, the opposite extremity of said spring being connected to a fixed point 14. Arranged in rear of the cut-out is a lever 15 which is fulcrumed between its ends and about centrally thereof on a pivot 16 which connects said lever to a support or hanger 17 which is bifurcated as shown to provide opposite portions between which the lever is placed and through which the pivot passes. The support 17 is mounted at its rear end on a vertical pivot 18 which allows the forward extremity of said support to swing laterally. A link 19 connects one arm of the lever 15 with the operating arm 11 of the cut-out. Another link 20 connects the other arm of the lever 15 with the pendant arm 21 of a pedal 22 which is pivotally mounted at 23 in the floor in advance of the operator's seat.

It will now be understood that when the operator desires to open the cut-out and allow a free exhaust directly to the atmosphere, it is only necessary for him to depress the pedal whereupon the lever 15 is rocked so as to pull on the operating arm 11 of the cut-out. The cut-out is thus held open as long as the operator presses against the pedal. When he releases the pedal by lifting his foot therefrom, the spring 13 acting on the operating arm 11 of the cut-out, returns said cut-out to its closed position. The lever 15 in connection with the support 17 acts as an equalizer so as to properly apply a pulling strain on the operating arm of the cut-out, the arrangement as a whole also avoiding lost motion between the several elements and thereby preventing rattling of the parts, the spring 13 serving to hold the entire operating mechanism under tension. Furthermore, the parts, under the arrangement and construction described, are not susceptible to rapid wear as in the case of the present day chain or cable and pulley arrangement and furthermore, there is no chain or other flexible connection to become jammed in the guiding pulley or pulleys.

around which it passes after leaving the operating pedal and before reaching the cut-out.

What I claim is:—

- 5 The combination with a motor car chassis, an engine mounted on the forward end thereof, an exhaust pipe leading rearwardly from said engine, and a muffler associated with said exhaust pipe, of a cut-out for said 20 pipe located adjacent to the engine, an operating arm for opening and closing said cut-out, a spring attached at one end to said operating arm extending forwardly therefrom and attached at its forward end to a fixed point, a hanger pivotally mounted at
- 10
- 15

one end thereof on a fixed part of the machine, a lever fulcrumed between its ends on the free end of said hanger, a link connecting said operating arm and one arm of said lever, a foot pedal, and another link connecting said pedal to the other arm of said lever, the latter being located in rear of both the cut-out arm and foot pedal.

In testimony whereof I affix my signature in presence of two witnesses.

PATRICK F. MARA.
